COMBINATION AMPLIFIER AND SPEAKER CABINET

Robert L. Warren, Mars, and Raymond A. Loturco, Wexford, Pa., assignors to Estey Musical Instrument Corporation, Harmony, Pa.

Continuation of design applications Ser. No. 12,455 and Ser. No. 12,456, June 20, 1968. This application Nov. 15, 1968, Ser. No. 14,675

Term of patent 14 years

Int. Cl. D14—01, 04

U.S. Cl. D26—14

FIG. 1.

FIG. 3.

FIG. 2.

FIG. 4FIG. 5FIG. 1 is a perspective view of a combination amplifier and speaker cabinet showing my new design;

FIG. 2 is a front elevation thereof;

FIG. 3 is a side elevation thereof;

FIG. 4 is a perspective view of a modified embodiment of the combination amplifier and speaker cabinet shown in FIG. 1; and

FIG. 5 is a front elevation thereof.

The control elements on the top of the amplifier are disclosed in broken lines for illustrative purposes only. The undisclosed rear is unornamented.

This is a continuation of design applications Ser. Nos. D. 12,455, and D. 12,456, filed June 20, 1968 and now abandoned.

We claim:

The ornamental design for a combination amplifier and speaker cabinet, as shown and described.
